SWASH PLATE TYPE ENGINE

Christopher George Nevatt and Francis West Shearer, Bristol, England, assignors to Nevatt Axial Engines Limited, Bristol, England, a British company

Application September 17, 1937, Serial No. 164,416
In Great Britain September 24, 1936

9 Claims. (Cl. 74—60)

This invention is for improvements in or relating to a swash-plate engine of the kind wherein the engine-shaft is provided with an inclined crank pin or the like which is rotatable in the swash-member and wherein means are provided for so constraining the movement of the swash-member that all points in a plane at right-angles to the inclined crank-pin and at equal distances therefrom traverse different paths of the same shape and wherein the connecting-rods of the engine are articulately connected to the swash-member. It is already known that the correct path of movement is a specific form of lemniscate.

The present invention is based on the observation that the lemniscate path is produced by the combined movements of a point rotating about an axis parallel with the engine-shaft and at the same time moving backwards and forwards along the axis, thus producing a form of helix. The lemniscate, as viewed along said axis, is a circle the equation of which may be found to be

$$y^2 + \left[z + \frac{R(\cos \alpha + 1)}{2} \right]^2 = \left[\frac{R(1 - \cos \alpha)}{2} \right]^2$$

where y and z are co-ordinates at right-angles to one another in a plane at right-angles to the engine-shaft, and α is the angle which the inclined crank-pin makes with the engine axis. The radius of the circle is equal to

$$\frac{R(1 - \cos \alpha)}{2}$$

The present invention consists in providing guide means which engage a part of the swash-member or a part connected thereto the contour of which guide means is such that the guided member moves in a path which, when projected on to a plane at right-angles to the engine-shaft, is a circle having the above equation. With this arrangement the constraint provided by the guide means coupled with the movement imparted to the swash-member by the crank-pin on which it is mounted will result in the desired lemniscate form of motion.

Assuming the guided member has a radius of K , the point of contact of centre of pressure between the guided member and guiding surface traverses a path which, viewed along a line parallel with the axis of the engine shaft is a circle or a part of a circle having the equation

$$y^2 + \left[z + \frac{R(\cos \alpha + 1)}{2} \right]^2 = \left[\frac{R(1 - \cos \alpha)}{2} + K \right]^2$$

The means for constraining the swash-member may comprise a member which is guided to move in a direction along the engine-shaft, a uni-

versal joint between said guide member and the swash-member, a loose connection either between said guided member and a part of said joint, or between two relatively movable parts of said joint, or between a part of said joint and the swash-member, which connection is arranged to permit relative movement between the parts it connects in a direction towards and away from the engine-shaft and in a direction transverse to the axis of the shaft; preferably it also limits those movements so that they lie within a cylindrical boundary which, when projected on a plane at right-angles to the engine-shaft, is a circle having the equation referred to above. In this arrangement the guided member and said connection constitute the guide means whereby a part of the swash-member is constrained to move around the cylindrical envelope. The words "universal joint" are intended to include both a ball-and-socket joint and a joint of the kind in which movement takes place about two axes at right-angles to one another, such for example, as a Hooke's-type joint. If the latter type of joint is employed, it is arranged so that one of the axes lies in a plane at right-angles to the inclined crank-pin.

It is a characteristic of a swash-member of the kind first referred to above that although points equidistant from and distributed around the inclined crank-pin in a plane at right-angles to the crank-pin all move in the same lemniscate form of path, at any one moment they are traversing different parts of the path. For example, while one point on the swash-member is traversing the end of a lemniscate, another point on the swash-member angularly disposed from the first said point by 90° will be at the cross-over point of the lemniscate. By guiding one part of the swash-member all other parts are constrained to move in the desired manner. If, however, a number of parts of the swash-member are guided, it is not necessary for each part to be constrained by its guide around the whole lemniscate but the combined effect of the guides must be such as to result in all the parts being constrained along the whole length of their lemniscates.

It will therefore be appreciated that a number of guide means may be associated with different parts of the swash-member distributed around the crank-pin, each of which may either be arranged to constrain its part of the swash-member to move along the whole of the path of the lemniscate or along only a part thereof, in which latter case, the other guide means collectively

constrain said first part to move along the remaining portion of the lemniscate.

A feature of the invention consists in that said guided member or members comprise one or other of the connecting-rods of the engine, which is or are guided to move in a straight line parallel with the engine-shaft and has associated therewith a universal joint and a connection in the manner referred to above. The provision of a connecting-rod moving in a straight line parallel with the engine-shaft is particularly useful in connection with internal-combustion engines in which the cylinders are arranged parallel with and distributed around the engine-shaft since the ends of the cylinders adjacent the swash-member may be closed and isolated from the chamber in which the swash-member is mounted. Furthermore, better balance is obtainable when the connecting-rod is moved in a straight line than in the previous arrangements in which the whole of the connecting-rod had imparted to it a wobbling motion.

The following is a description of a number of constructions of swash-plate mechanism suitable for use in internal-combustion engines, reference being made to the accompanying drawings, in which—

Figure 1 is a section in a plane containing the engine-shaft axis through those parts of the mechanism which guide the connecting-rod and connect it to the swash-member;

Figure 2 is a half-section on the line 2—2 of Figure 1 and an end elevation looking in the direction of the arrows of Figure 1;

Figure 3 is a plan view of Figure 1 in which the guide means for the connecting-rod are shown in section;

Figure 4 is a similar section to that of Figure 1 of an alternative form of construction in which one part of a ball-and-socket joint is secured to the engine connecting-rod and in which a part of the swash-member slidingly engages the other part of the joint;

Figure 5 is a section on the line 5—5 of Figure 4;

Figure 6 is a similar section to that of Figure 1 of an alternative construction in which one part of the universal joint is secured to the connecting-rod and the other part of which is secured to the swash-member, and in which a sliding connection is provided between the two parts of the universal joint;

Figure 7 is a section on the line 7—7 of Figure 6; and

Figure 8 is a half-section on the line 8—8 of Figure 6 and a half-plan view of Figure 6.

All the constructions about to be described are applicable to an internal-combustion engine in which the cylinders are arranged parallel with and distributed around the engine-shaft. The engine-shaft is provided with an inclined crank-pin which is rotatable in a swash-member. Each cylinder contains a piston having a connecting-rod which is articulately connected to the swash-member.

Referring now to the construction shown in Figures 1 to 3, the connecting-rod 10 is provided with a head 11 which is engaged by a flange 12 on a nut-member 13. The nut is arranged to engage a screw-threaded shank 14 on a plug 15. The plug is externally threaded and engages an internally-threaded sleeve 16. A similar plug 17, without a central shank, is arranged to engage the other end of the sleeve. The sleeve is a good sliding fit in a hollow cylindrical guide-member 18 which is fixed to the engine casing so that

its axis lies parallel with the engine-shaft. Thus the connecting-rod 10 is guided to move along said axis. Any or all of said connecting-rods may be guided to move in this manner.

The swash-member 19 is circular in contour, 5 is mounted on the inclined crank-pin 5 of the crankshaft 6 and has secured to it a number of radially-extending arms 20 having spherical heads 21, one arm being provided for each connecting-rod. The arm extends through a longitudinal slot 26 in the guide-member 18. The spherical head is embraced by a two-part socket member 22 which is straddled by a clamping member 7 having on either side thereof tubular trunnions 23. Each tubular trunnion is internally 15 threaded to receive a clamping screw 8 and is surrounded by a hard steel cap-member 24 having a cylindrical outer surface. The trunnions with their caps are located in cylindrical recesses 25 formed in the plug members 15 and 17. The 20 diameters of the cap-members 24 and the cylindrical recesses 25 are so selected that when the trunnions traverse the peripheral wall of the recesses the axis of the trunnion describes a circle 25 having the equations referred to above.

The above mechanism, in effect, comprises a ball-and-socket joint, one part of which is fixed to the swash-member and the other part of which is connected to the guided end of the connecting-rod through a loose connection having a guide-member, viz. the plugs 15 and 17 with a cylindrical recess. Since this cylindrical recess is reciprocated backwards and forwards in a straight line it has a cylindrical envelope, the projection of which on a plane at right-angles to the engine- 35 shaft is a circle having the above equation.

The torque reaction of the engine-shaft is transmitted between the cap-members 24 and the peripheral wall of the cylindrical recess but where each connecting-rod is provided with the mechanism the combined surfaces are well able to withstand the loads imparted to them. As already indicated above, however, it may not be necessary for each mechanism to be provided with a complete guiding surface so long as the combined effect of all the guiding surfaces is to effect the required lemniscate movement.

Referring now to the construction shown in Figures 4 and 5, a socket-member 27 of a ball-and-socket joint may be secured to the end of any or all of the connecting-rods 28. The socket-member is formed in two parts, one of which is formed integral with the connecting-rod 28 and the other of which is secured to the first part by bolts 29 (see Figure 5). These bolts pass 55 through lugs 30 formed on either side of the socket-member, which lugs are provided with flat faces 31 which are engaged by guide-ways 32 fixed to the engine casing, so as to guide the connecting-rod in a line parallel with the engine-shaft. The ball 33 of the joint is formed in two parts, one of which is provided with an internally-threaded recess which engages a threaded projection on the other part, as indicated at 34. The ball is provided with a screw-threaded stem 65 35 which projects out through a slot 36 in the socket-member and is provided with a nut 37 and a washer 38 which latter engages an outer surface of the socket-member. The stem extends through a block 9 which engages the sides of the 70 slot. Formed in the ball 33 is a diametrically-extending slot 39 having flat sides 40 and a peripheral wall 41. Fixed to the swash-member 42 are a number of radially-extending arms, one- 75 for each connecting-rod, which are provided with

heads 44 having flat faces which engage the flat sides 40 of the slot and which are circular in contour, as seen in Figure 5. The arms 43 extend through a slot 45 formed in the socket-member. The head 44 contacts with the peripheral wall 41 and precesses around it. The contour of the peripheral wall is so selected that the point of contact between it and the head traverses a path which when projected on a plane at right-angles to the engine-shaft is a circle having an equation as set out at the commencement of the specification.

In effect, the above mechanism comprises a ball-and-socket joint, one part of which is secured to the connecting-rod and the other part of which is secured to the swash-member through a connection which provides the requisite guiding means for effecting the desired lemniscate path. A similar mechanism may be associated with each connecting-rod but, as indicated above, a complete elliptical bearing surface need not be provided in each mechanism.

Referring now to the construction shown in Figures 6 to 8, the end of the connecting-rod 46 is secured in a socket in a bearing-block 47 by a bolt 48. The bearing-block 47 has flat sides 49 (see Figure 7) which slidably engage the side walls of a channel-shaped guide member 50. The bearing-block is provided with a cylindrical bore which is closed at one end by a cap-member 51 having an externally-threaded rim which engages the internally-threaded part of said bore. A flat cover-plate 52 is secured over the open end of the channel-shaped guide-member so as to bear against the cap-member 51. The cover-plate is secured in position by an angle-plate 53 having flanges 54 which engage recesses 55 in the side walls of the guide-member. Bolts 56 extend through the angle-plate and engage threaded holes in the bottom wall 57 of the channel-shaped guide-way. The channel-shaped guide-way is so disposed as to guide the connecting-rod to move in a straight line parallel with the engine-shaft. Located in the cylindrical bore of the bearing-block is a guide-block 58 having a slot formed therein, the two opposite walls 59 of which are flat, as seen in Figure 6, and the other two opposite walls 60 are curved, as seen in Figure 7. The outer surface of the guide-block is cylindrical and forms a good rotating fit in the cylindrical bore of the bearing-block.

As in the previous constructions, the swash-member is provided with a number of radially-extending arms 61, one for each connecting-rod. Each of the arms extends through a slot 62 formed in the bottom wall 57 of the channel-shaped guide-member. As will be seen from Figure 7, the end of the radial arm is provided with a bored boss 63. Each end of the boss is encircled by an annular cap-member 64 and a bolt 65 extends through the holes in the two annular cap-members so that they are clamped together on each side of the boss.

Two opposite sides of the annular cap-members are flat and engage the flat sides 59 of the slot in the guide-block. The other opposite sides are spherically shaped, as indicated at 66 in Figure 7. This arrangement, in effect, provides a Hooke's-type joint in which one pivot axis is constituted by the joint between the radial arms 61 and the annular cap-members 64 and the other pivot of the joint which is at right-angles thereto is constituted by the cylindrical bearing between the bearing-block 58 and the guide-block 47. The aforesaid connection is provided between the two

parts of the joint and in order that the necessary lemniscate movement may result, the curve requires to be egg-shaped. It will be appreciated that through one cycle of movement the guide-block 58 will be oscillating about an axis at right-angles to the engine-shaft and the annular cap-members will be precessing around the curved surface. At any one moment that part of the curved surface with which the annular cap-member is in contact should, when projected on a plane at right-angles to the engine-shaft, be a circle. Since, however, that surface is oscillating about the aforesaid axis, it will require to be egg-shaped, as aforesaid.

We claim:

1. A swash-plate engine comprising an engine-shaft having an inclined crank-pin, a swash-member mounted on said crank-pin, a number of connecting-rods for the engine pistons articulately connected to said swash-member, a guide extending in a direction along the engine-shaft, a part movable along said guide, a universal joint between said guided parts and the swash-member, a loose connection between two relatively movable parts of said joint, which loose connection comprises a circular part, within an encircling guide-surface, of such shape that the path of movement of the point of contact between those parts as viewed along a line parallel with the axis of the engine, is a circle having the equation

$$y^2 + \left[z + \frac{R(\cos \alpha + 1)}{2} \right]^2 = \left[\frac{R(1 - \cos \alpha)}{2} + K \right]^2$$

2. A swash-plate engine comprising an engine-shaft having an inclined crank-pin, a swash-member mounted on said crank-pin, a number of connecting-rods for the engine pistons articulately connected to said swash-member, a guide extending in a direction along the engine-shaft, a part movable along said guide, a universal joint between said guided parts and the swash-member, a loose connection between a part of said joint and the swash-member, which loose connection comprises a circular part, within an encircling guide-surface, of such shape that the path of movement of the point of contact between those parts as viewed along a line parallel with the axis of the engine, is a circle having the equation

$$y^2 + \left[z + \frac{R(\cos \alpha + 1)}{2} \right]^2 = \left[\frac{R(1 - \cos \alpha)}{2} + K \right]^2$$

3. A swash-plate engine comprising an engine-shaft having an inclined crank-pin, a swash-member mounted on said crank-pin, a number of connecting-rods for the engine pistons articulately connected to said swash-member, a number of guide means arranged to engage respectively a number of parts moving with the swash-member and which guide means are adapted to apply circular constraint to the guided parts during different parts of the cycle, so that the sum effect of the constraints is to impart to a point on the swash-member a path of movement which when projected on to a plane at right-angles to the engine-shaft is a circle having the equation

$$y^2 + \left[z + \frac{R(\cos \alpha + 1)}{2} \right]^2 = \left[\frac{R(1 - \cos \alpha)}{2} \right]^2$$

4. A swash-plate engine comprising an engine-shaft having an inclined crank-pin, a swash-member mounted on said crank-pin, a number of connecting-rods for the engine pistons, means for guiding each connecting-rod to move in a

- straight line parallel with the engine-shaft, a universal joint for connecting each connecting-rod to the swash-member, a loose connection between two parts of said universal joint, which loose connection is adapted to permit relative movement between the parts it connects in a direction towards and away from the engine-shaft and in a direction transverse to the axis of the shaft.
10. 5. A swash-plate engine comprising an engine-shaft having an inclined crank-pin, a swash-member mounted on said crank-pin, a number of connecting-rods for the engine pistons, means for guiding each connecting-rod to move in a straight line parallel with the engine-shaft, a universal joint for connecting each connecting-rod to the swash-member, a loose connection between a part of the universal joint and a part of said swash-member, which loose connection is adapted to permit relative movement between the parts it connects in a direction towards and away from the engine-shaft and in a direction transverse to the axis of the shaft.
15. 6. A swash-plate engine comprising an engine-shaft having an inclined crank-pin, a swash-member mounted on said crank-pin, a number of connecting-rods for the engine pistons, means for guiding the connecting-rods to move parallel with the engine-shaft, a spherical socket connected to a connecting-rod, a ball in said spherical socket, and having a diametrically-extending slot with flat sides and a peripheral wall, a disc-like part attached to the swash-member and extending into the aforesaid slot in said wall, the peripheries of which slot and disc-like member are so shaped that the point of contact between them moves in a path which as viewed along a line parallel with the axis of the engine is a circle having the equation
20. 40. $y^2 + \left[z + \frac{R(\cos \alpha + 1)}{2} \right]^2 = \left[\frac{R(1 - \cos \alpha)}{2} + K \right]^2$
7. A swash-plate engine comprising an engine-shaft having an inclined crank-pin, a swash-member mounted on said crank-pin, a number of connecting-rods for the engine pistons, means for guiding the connecting-rods to move parallel with the engine-shaft, a block pivotally attached to the swash-member to rock about an axis in the plane of the swash-member at right-angles to the crank-pin, a member having a slot adapted slidably to engage said block, and having a cylindrical outer surface arranged with its axis normal to the engine-shaft and to the first said axis, a part fixed to a connecting-rod and having a cylindrical socket arranged rotatably to engage said cylindrical surface, which block and slot have flat engaging faces and peripheral surfaces

of such shape and size that the line of contact between them traverses a circular path having the equation

$$y^2 + \left[z + \frac{R(\cos \alpha + 1)}{2} \right]^2 = \left[\frac{R(1 - \cos \alpha)}{2} + K \right]^2 \quad 5$$

8. A swash-plate engine comprising an engine-shaft having an inclined crank-pin, a swash-member mounted on said crank-pin, a number of connecting rods for the engine pistons articulately connected to said swash-member, a guide extending in a direction along the engine-shaft, a part movable along said guide, a universal joint between said guided part and the swash-member, a loose connection between said guided part and a part of said universal joint, which loose connection comprises a circular cap member rotatably mounted on said part of the universal joint and a circular guide surface formed in said guided part and arranged to encircle and engage said cap member, which cap member and circular guide surface are so shaped that the path of movement of the point of contact between the cap member and the guide surface, as viewed along a line parallel with the axis of the engine, is a circle having the equation

$$y^2 + \left[z + \frac{R(\cos \alpha + 1)}{2} \right]^2 = \left[\frac{R(1 - \cos \alpha)}{2} + K \right]^2 \quad 10$$

9. A swash-plate engine comprising an engine-shaft having an inclined crank-pin, a swash-member mounted on said crank-pin, a number of connecting rods for the engine pistons articulately connected to said swash-member, a guide extending in a direction along the engine-shaft, a part movable along said guide, a universal joint between said guided part and the swash-member, a loose connection between said guided part and a part of said universal joint, which loose connection comprises a cylindrical cap member rotatably mounted on said part of the universal joint and having a flat end face and a cylindrical recess in said guided part having a larger diameter than said cap member and having a flat end face, which cap member is disposed within the recess with its periphery in contact with the cylindrical wall of the recess and with its flat end face in contact with the flat face of said recess, the contours of which cap member and recess are so shaped that the path of movement of the point of contact between those parts as viewed along a line parallel with the axis of the engine is a circle having the equation

$$y^2 + \left[z + \frac{R(\cos \alpha + 1)}{2} \right]^2 = \left[\frac{R(1 - \cos \alpha)}{2} + K \right]^2 \quad 15$$
